FLEXIBLE UMBRELLA RIB

Thelma Ione Fortner, Newark, N. J., assignor to
Staten Frame Manufacturing Company, Inc.,
New York, N. Y., a corporation of New York

Application April 4, 1950, Serial No. 153,975

3 Claims. (Cl. 135—31)

1

This invention relates to umbrella frames and more particularly to a new and improved construction of the rib and spreader elements of umbrella frames.

In use, the frame of an umbrella, including the ribs and spreader elements, are subject to lateral and vertical bending strains, the most typical being the curved bend imparted to the ribs of the umbrella as the latter are restrained by the cover or canopy when the umbrella is opened. However, the umbrella elements also are subjected to considerable bending and twisting during ordinary use and to unusual strains such as the reverse bend when the umbrella is blown inside out. The usual channel, or U-shaped type of umbrella frame element is not of a suitable cross-sectional configuration to withstand the strain of reverse bending nor other severe twisting or bending. Although attempts have been made to strengthen the rib elements locally at the crown or cap of umbrella frames and also at the juncture of the ribs with the spreader elements, there has been no successful improvement to strengthen the rib and spreader elements throughout their length.

The object of the present invention is to provide umbrella frame elements which are of considerably stronger construction than existing types and with sufficient flexibility to be capable of withstanding both the ordinary and severe strains of usage throughout their length and which may be produced relatively inexpensively and without adding appreciably to the weight of the umbrella.

Another object of the invention is to provide an umbrella frame having frame elements of sufficient strength to withstand the strain when the umbrella is blown inside out.

To describe the invention, reference is made to the drawings, wherein:

Fig. 1 is a portion of the frame of an umbrella in the opened position;

Fig. 1a is a detail of the end portion of an umbrella element;

Figs. 2, 2a, 3, 3a, 4, 4a, 5 and 5a are cross-sectional views indicating the manner of forming and the final shape of several forms of umbrella frame elements embodying the invention;

Fig. 6 is a side view of a joint of the spreader and rib elements of the invention, and

Fig. 7 is a sectional view of the joint taken along the line 7—7 in Fig. 6.

The umbrella frame elements of the invention are shaped from strips of sheet metal which are folded or rolled laterally to form parallel tubu-

lar portions connected by an intermediate, or web portion. Several preferred forms of the invention are illustrated in Figs. 2a, 3a, 4a and 5a.

Referring to Figs. 2 and 2a, a sheet metal strip 1 of suitable width is laterally folded upon itself so that the edges or sides 2 of the strip are folded or rolled to form round or tubular shape members 3. The central portion 4 of the strip forms a web or connecting portion between the two tubular portions 3 which is substantially tangent to the two coiled tubular portions and parallel to a line drawn through the axes of the coiled portions. Thereafter the metal strip is suitably heat treated to give the metal appropriate spring.

Referring now to Figs. 3 and 3a which shows the cross-section of an alternate form of the invention, the edges 5 of the sheet metal strip are folded or rolled in upon the strip on opposite sides thereof to provide tubular portions 6 which are formed in a figure eight configuration with the central portion 7 of the strip forming the connecting web portion. The central portion 7 is straight and substantially tangent to the two coiled or tubular members 6 and intersects a line 25 passing through the axes of the coiled portions 6.

Another form of the invention is illustrated in Figs. 4 and 4a wherein the edge 8 of sheet metal is folded upon the strip and coiled laterally to the edge 9 to effect a member having a continuously spiral cross-sectional configuration shown in Fig. 4a and which might be defined by saying that it is comprised of two substantially concentrically disposed tubular members 10 and 10a connected by a curved web integral with said members 10, 10a.

Another modification or alternate form of the invention, as shown in Figs. 5 and 5a may be produced by laterally folding or rolling the edges 11 upon the strip to form tubular members 12 and thereafter crimping the tubular portions 12 inwardly toward each other and pressing the central portion 13 downward so that it forms a substantially straight connecting web centrally disposed on a line passing through the axis of the two circular portions 12.

The umbrella frame elements are made from strips of sheet metal stock of suitable gauge. Because of the greater structural strength of the finished rib and spreader elements of this invention the sheet metal stock may be of lighter gauge than that used for channel type ribs. However, the standard gauge is also suitable. The strips are passed between rollers to fold or roll them into the forms shown in Figs. 2a, 3a, 4a and 5a. In the case of the form shown in Fig. 5a after the

rolling has been performed the web 13 is pressed downward while the tubular portions 12 are crimped inwardly. In all cases the width of the strip is uniform throughout its length and is slightly wider than the width of the metal strip used in the channel type frame elements. Ends of the formed ribs and spreader elements are crimped and rounded, as shown in Fig. 1a. The additional width of the metal strip is utilized to provide an additional strength at these points. Holes are thereafter cut in the crimped lugs provided at the ends of the rib and spreader elements.

The rib members are oriented so that the axes of the two tubular portions lie in a plane parallel to the surface of the cloth or other fabric of the canopy when the ribs are assembled in the frame, and the spreader elements are mounted so that the tubular portions are in side by side relationship with their respective axes lying in a conical surface, the apex of which is the central shaft 35. The shaft or central pole 35 of the umbrella made of a standard type is also provided with the usual annular slotted cap or crown 16. The crimped lugs 14 provided at the ends of the ribs are introduced into the slots 15 of the crown 16 as shown in Fig. 1 and the annular retaining wire 17 of the cap or crown 16 is passed through the holes 18 provided in the lugs 14. The sleeve 19 is positioned on the rib element 20 at the juncture of the rib with the spreader 21. The sleeve may be soldered or otherwise suitably fixed in a position on the rib element. A slotted lug 22 is provided on the under side of the sleeve to receive the crimped spreader lug 23 and a pin 24 is passed through holes 25 provided in the sleeve lug, and through a similar hole provided in the crimped spreader lug 23. The spreader is attached to the runner 26 in the usual fashion, that is, by inserting the crimped spreader lug 27 provided at the inner end of the spreader into a slot 28 provided in the runner. An annular retaining wire 29 is passed through the hole 30 in the lug 27. The outer end 31 of the rib 20 is suitably crimped to receive the standard type tip 32. Thereafter the canopy of cloth or other fabric may be attached to the frame in the usual manner.

It will be noted that this invention can be readily adapted to standard umbrella manufacturing procedures because the rib and spreader elements are adapted to be combined in the usual manner with standard crown and runner connecting means.

Use of the sleeve 19 which embraces the rib at the juncture of the spreader is particularly advantageous in that the strength and cross-sectional configuration of the ribs is not weakened by crimping or slotting at the point of juncture.

It will be noted particularly that the rib and spreader elements will have considerably greater strength to withstand the lateral and vertical bending strains because of the dual tubular configuration with the connecting central web; the use of the dual tubular members permitting

greater flexibility than can be achieved with the channel or the single tubular types of configuration.

When pressure is applied against the back or arc of the channel type umbrella element, the free sides tend to spring outward and there is no restoring or retaining force whereas in the present invention, considering the structure as two channels, it will be noted that one side of each is retained by the central web and the other side is either yieldingly retained by abutting a corresponding free side as in the case of the form shown in Fig. 2a, or the free side is so oriented that it is not subject to outward spreading. The single tubular form of elements similarly are not as satisfactory as structures of the present invention because there are no free ends which can be yieldingly retained.

Although the width of the strip of sheet metal is slightly wider than used to form the standard channel type of umbrella frame elements, it will be appreciated, as noted above, that the use of the cross-sectional configuration described in this invention makes it possible to utilize a thinner gauge of metal and at the same time having sufficient strength and greater flexibility without adding to the weight of the frame.

It will be appreciated that it is not intended to limit the invention to the forms shown in the application and that the various features and elements in the combinations and relations described may be altered and modified in ways other than those suggested without departing from the spirit and scope of the invention.

What is claimed is:

1. An improved umbrella frame element formed of a strip of sheet metal which has a configuration in cross-section comprising two substantially circular portions connected by a straight portion.

2. An improved umbrella frame element formed of a strip of sheet metal which has a configuration in cross-section comprising two substantially circular portions and a substantially straight portion connecting said circular portions along a line passing through the axes of the two circular portions.

3. An umbrella frame element which has a configuration in cross-section including two end portions connected by a straight portion, said end portions comprising substantially complete circles.

THELMA IONE FORTNER.
